US0D1081260S

(12) **United States Design Patent** (10) Patent No.: **US D1,081,260 S**
(45) Date of Patent: ** *Jul. 1, 2025

(54) **BEVERAGE CONTAINER**

(71) Applicant: **True Fabrications, Inc.**, Seattle, WA (US)

(72) Inventors: **Ryan William Hume**, Seattle, WA (US); **Chastity Steben**, Puyallup, WA (US)

(*) Notice: This patent is subject to a terminal disclaimer.

(**) Term: **15 Years**

(21) Appl. No.: **29/882,732**

(22) Filed: **Jan. 18, 2023**

(51) LOC (15) Cl. **07-01**
